MASONRY GUIDE LINE HOLDER

Barney F. Power, Orange, Calif.

Application October 26, 1956, Serial No. 43,536

Term of patent 14 years

(Cl. D51—1)

Fig. 1.

Fig. 2.

Fig. 3.

Fig. 4.

Fig. 5.

Figure 1 is a rear elevational view of the masonry guide line holder, showing my new design;

Figure 2 is an end elevational view of the holder, as viewed from the left in Figure 1;

Figure 3 is a front elevational view of the holder;

Figure 4 is an end elevation, as viewed from the left in Figure 3; and

Figure 5 is a side elevation of the holder.

Both sides of the holder are identical, and are constructed as shown in Figure 5.

I claim:

The ornamental design for a masonry guide line holder, substantially as shown and described.
